UNITED STATES PATENT OFFICE.

EDWARD DALLIG, OF POUGHKEEPSIE, NEW YORK.

MORTISING MACHINE.

Application filed December 14, 1923. Serial No. 680,653.

To all whom it may concern:

Be it known that I, EDWARD DALLIG, a citizen of the United States, residing at Poughkeepsie, in the county of Dutchess and 5 State of New York, have invented certain new and useful Improvements in Mortising Machines, of which the following is a specification.

This invention relates to improvements in 10 mortising machines, or that class of apparatus used in cutting recesses in solid substances, and more particularly to a type of machine for making openings of uniform size and shape but available to suit.

15 The main object of the invention is to provide a mechanism capable of automatically forming one or more spoke receiving recesses in the inner side of a wheel rim of solid, "built up" or laminated construction, 20 such for instance as are used for steering wheels of self propelled vehicles.

Another purpose is to produce a device by which a plurality of power driven routing cutters are caused to remove the material 25 in an easy and rapid manner, all of the cutters being universally actuated and controlled from a single point.

A further aim is in the provision of a mortising machine for wheel rims capable 30 of operating on rims of varying diameter, being readily adjusted as required.

These and other miscellaneous aims, objects and purposes, which will later appear, are accomplished by the novel construction, 35 combination and arrangement of parts hereinafter described and shown in the accompanying drawings, forming a material part of this disclosure, and in which:—

Figure 1 is a plan view of an embodiment 40 of the invention, the cover portion being partially broken away to disclose the interior.

Figure 2 is a partial plan and horizontal 45 sectional view of the same.

Figure 3 is a transverse sectional view taken on line 3—3 of Figure 2.

Figure 4 is a side view of a conventional type of hand wheel, drawn to a smaller scale.

50 Figure 5 is an enlarged plan view of one of the cutter carrying compound slides.

Figure 6 is an enlarged fragmentary sectional view showing the shape of cut produced in the wheel rim.

55 Figure 7 is a plan view similar to Figure

5 but showing a modification in construction.

Figure 8 is a sectional view of the rim as mortised by the device shown in Figure 7.

Figure 9 is a sectional view of the cutter, 60 the section being taken on line 9—9 of Figure 5.

Referring to the drawings more in detail, Figure 4 shows a conventional type of steering wheel composed of a two part rim 15, 65 joined at 15', of solid, sectional, laminated or other construction, usually made of wood and having spokes 16 radiating from a hub 17, the outer ends of the spokes being increased in width, as at 18 and tight-fitted 70 to correspondingly shaped recesses 19 in the interior surface of the wheel rim.

As before stated, the main object of the invention is to provide a mechanism for cutting, routing or removing stock from the 75 rim into which the ends of the spokes or arms are engaged.

Said mechanism comprises a power driven shaft 20 disposed in a vertical plane, its upper end being guided in bearings 21 and 80 22 formed on plates 23 and 24, the former being the lowermost.

Said plates are segmental in shape, symmetrical in outline and provided with outstanding lugs having between them shouldered studs 25 maintaining the plates in rigid spaced engagement, and also a third or cover plate 26, secured by the nuts 27 on the studs.

Fixed on the shaft 20 is a bevel gear 28 90 with which meshes pinions 29 secured on spindles 30 rotatably mounted on blocks 31 fixed on the plates 23, the inner end of the spindles also being engaged in blocks 32 fixed on the plate 24, these spindles being 95 positioned approximately forty-five degrees apart.

Carried on the outer ends of the spindles 30 are universal joints 33 connected by telescopic elements 34 with similar universal joints 35 fixed on the ends of spindles 36 mounted in sleeves 37 and carrying chucks and convenient holding means 38 for the routing cutters 39.

Said sleeves 37 are rotatably mounted in 105 slides 40 movable in a plane parallel to the spindles 36, said slides being engaged in other slides 41, operable on guides 42 fixed on the plate 23 at right angles to the spindles 36.

The bearings in the slides 40 are provided with caps 40', the centers of which are provided with holes into which project pins 43 of the eccentric discs 44 disposed in contact with the lower surface of a plate 70 secured in the plate 24.

Said discs have axial spindles 45 which extend thru the plate 26 and mounted on the spindles are spur gears 46 above which are 10 collars 47.

Meshing with the spur gears 46 is another gear 48, relatively of large diameter, mounted on a spindle 49 rotatable in the plates 24 and 26 arranged radially of the 15 shaft 20 and midway of the blocks 31.

The spindle is caused to return to its original normal rotative position by a torsion spring 52, the same opposing an operative handle 53 by which the spindle and 20 gear can be rotated.

It will be understood that when the handle 53 is rotated, the gears 46 are turned and therefore the discs 44, in which the pins 43 are engaged, causing the slides to move 25 and the cutters 39 to advance in a curved path as they are rotated, thus forming a pocket or recess 19 as shown.

Said slides are provided with tension springs, respectively 54 and 55 which operate to return the slides to normal position.

In Figure 5 a modification is shown by which the recess 19' may be formed, the same differing mainly in having parallel slides and a curved bottom, in place of a 35 semi-circular cut.

To accomplish this a cam 60 is fixed on the spindle 45, the cam having an arcuate rear portion 61 normally in contact with a pin 62 fixed in the slide 40 and in its front portion is a slot 63 slidably containing a block 64 in which the stem 43 is received.

The opposite end 65 of the cam is adapted to make contact with a fixed arcuate plate 66 secured to the slide 40 in such manner 45 that when the point 65 engages the plate, the upper slide is compelled to move in a straight path, producing the sides of the recess, the bottom of which will conform to the inner edge surface of the plate 66.

Figure 8 shows a recess 19' having parallel side walls and a straight flat bottom, the same being produced by the device shown in Figure 7.

Secured to the upper side of the plate 24 is 55 a plate 70 having a longitudinal slot 71 with a right angular extension 72, the ends being square and the sides parallel.

Movable in these guide slots is a block 73 in which the stud 43 is received, said stud

also passing through a guide 74 operable in 60 a slot 75 formed in a lever arm 76 rigidly attached to the spindle 45.

Thus it will be seen that the cutter 39 is caused to advance straight into the rim and move laterally by reason of the slots 72 until the opposite end of the recess has been reached, whereupon it may move reversely until it has resumed its initial position.

From the foregoing it will be seen that a routing device by which a pair of cutters 70 is driven and controlled has been disclosed in the preferred form of its embodiment, but it will be understood that, changes may be made without conflicting with the scope and tenor of the claims hereto appended. 75

Having thus described my invention, what I claim as new and desire to secure by Letters Patent, is:—

1. A mortising machine comprising a power shaft, spindles geared to said shaft 80 and arranged radially thereto at an angle forming an equal division of a circle end-thrust tool carrying spindles connected by universal joints to be driven from said first mentioned spindles; crossed slides upon 85 which the tool carrying spindles are mounted to be given predetermined endwise and lateral movements, a crank for each set of compound slides imparting thereby to each tool the desired movement and a common 90 means for rotating the said cranks.

2. A mortising machine comprising a pair of spindles each carrying an end-thrust cutter, spindles driven from a common shaft having a universally jointed connection for 95 rotating said tool carrying spindles, a pair of crossed slides upon which each of said tool carrying spindles are mounted to be moved endwise and laterally, a crank for each set of crossed slides and a single wheel 100 geared to both cranks.

3. A mortising machine comprising a pair of spindles each carrying an end-thrust cutter, spindles driven from a common shaft having a universally jointed connection for 105 rotating said tool carrying spindles, a pair of crossed slides upon which each of said tool carrying spindles are mounted to be moved endwise and laterally, a crank for each set of crossed slides, a single wheel 110 geared to both cranks, manual means for operating the geared wheel, and automatic means for returning the gear and slides to normal position.

In witness whereof I have affixed my signature.

EDWARD DALLIG.
